DESIGN FOR A HOUSECOAT OR SIMILAR ARTICLE

Paige Salfeety, New York, N. Y.

Application December 2, 1941, Serial No. 104,436

Term of patent 3½ years

To all whom it may concern:

Be it known that I, Paige Salfeety, a subject of the King of Great Britain, residing in New York city, county of New York, and State of New York, have invented a new, original and ornamental Design for a Housecoat or Similar Article, of which the following is a specification, reference being had to the accompanying drawing, forming part thereof, wherein,

I claim:

The ornamental design for a housecoat or similar article, substantially as shown.

PAIGE SALFEETY.
